(57) **CLAIM**

We claim the ornamental design for a television receiver, as shown and described.

DESCRIPTION

FIG. 1 is a front perspective view of a television receiver showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 as illustrated in FIG. 1;

FIG. 10 is an enlarged view of the encircled portion 10 as illustrated in FIG. 1;

FIG. 11 is an enlarged view of the encircled portion 11 as illustrated in FIG. 4;

FIG. 12 is an enlarged view of the encircled portion 12 as illustrated in FIG. 8; and,

FIG. 13 is a front perspective view thereof, shown with the stands in a second position.

The dash-dash broken lines in the figures depict portions of the television receiver which form no part of the claimed design.

The dot-dot-dash broken lines encircling portions of the claimed design that are illustrated in enlargements form no part of the claimed design.

1 Claim, 10 Drawing Sheets
